UNITED STATES PATENT OFFICE.

DANIEL A. TRADESCO, OF PRICEBURG, PENNSYLVANIA.

SPIKE FOR BASE-BALL SHOES.

1,072,794.

Specification of Letters Patent. Patented Sept. 9, 1913.

Application filed April 12, 1912. Serial No. 690,225.

To all whom it may concern:

Be it known that I, DANIEL A. TRADESCO, a citizen of the United States, residing at Priceburg, in the county of Lackawanna 5 and State of Pennsylvania, have invented certain new and useful Improvements in Spikes for Base-Ball Shoes, of which the following is a specification, reference being had to the accompanying drawings.

10 This invention comprehends certain new and useful improvements in spikes for base ball shoes and the invention has for its primary object a simple, durable and efficient construction of device of this character, the parts of which are so arranged 15 that they may be cheaply manufactured and readily assembled, and will prevent injury to the players such as are incidental to spikes of the kind heretofore ordinarily used.

20 The invention also has for its object an improved device of this character which will automatically clear itself of dirt and grass so that the spike will at all times be in proper condition. And the invention aims to 25 generally improve devices of this class and to render them more useful and commercially desirable.

With these and other objects in view as will more fully appear as the description 30 proceeds, the invention consists in certain constructions, arrangements and combinations of the parts that I shall hereinafter describe and claim.

For a full understanding of the invention 35 reference is to be had to the following description and accompanying drawings, in which—

Figure 1 is a bottom plan view of a shoe equipped with two of my improved spikes; 40 Fig. 2 is an enlarged sectional view on the line 2—2 of Fig. 1 and with the parts in normal position; Fig. 3 is a bottom plan view of the base plate of the device; and Fig. 4 is a similar view of the spike carrying plate.

Corresponding and like parts are referred to in the following description and designated in the accompanying drawings by like reference characters.

50 In practice I propose the use of two of my improved spikes for each shoe, but as they are both alike, a description of one will suffice.

My improved spike includes a base plate 55 1 which is formed with any desired num-

ber of apertured ears 2 designed to receive screws or similar fastening devices whereby said base plate may be readily attached to the sole of the shoe. The base plate 1 is formed with an annular flange 3 which is 60 interiorly screw threaded as indicated at 4 for engagement with the exterior screw threads 5 of a spike plate 6, said spike plate in the present instance being formed with three curved and circularly arranged blades 65 or flanges 7 slightly separated from each other at their adjacent ends, whereby they may obtain a firm hold in the ground. The blades or flanges 7 are sharpened as indicated at 8. Within the circle of the flanges 70 7 a concavo-convex disk 9 is mounted, and back of the said disk is a spiral spring 10 exerting its pressure on said disk to move it outwardly whereby the central portion of the disk will, when there is no pressure on 75 the disk, lie outside of the plane of the sharpened edges 8 of the flanges 7. The convex face of the disk 9 extends outwardly so that the disk 9 forms a cover for the spring 10 and prevents any dirt, grass, or 80 sod entering between the spirals of the spring and hindering the action of the same.

From the foregoing description in connection with the accompanying drawings, the 85 operation of my improved spike for base-ball shoes will be apparent.

In the practical use of the device, when the player plants his foot on the ground, it is obvious that the disk 9 will move inwardly 90 against the pressure of the spring 10 and consequently the sharpened edges 8 of the blades or flanges 7 will engage the ground and enable the player to obtain a firm hold thereon with his feet. As soon as the player's foot is lifted from the ground, the spring 95 10 is permitted to act and the disk 9 is moved outwardly again to its outward position whereby the plate will be prevented from being clogged up with sod, dirt or grass and the spike will at all times be maintained in proper condition. Preferably, in order to limit the outward movement of the cupped disk 9, the plate 6 is formed on the inner wall of its flanges 7 with shoulders 100 7^a designed to engage the edge of the disk, as best illustrated in Fig 2. As the central portion of the disk 9 extends outside of the plane of the sharpened edges 8 of the flanges 7, the spike will be rendered resilient owing 110 to the pressure of the spring 10 against the

inner face of the disk 9, thereby tending to increase the speed of the player while running.

In the use of the ordinary spikes, the 5 players are frequently badly cut by coming into contact with the spikes of a sliding player, but with a spike constructed according to my invention, protection is afforded the players from the sharp edges of the 10 spike because of the curvature of the disk. Should my device come into contact with the limb of a player, the disk 9 being in advance of the sharpened edges 8 of the flanges 7, will glide off the limb of the player and 15 thereby prevent the edges of the flanges from striking the limb.

While the accompanying drawings illustrate what I believe to be the preferred embodiment of my invention, it is to be understood that the invention is not limited thereto but that various changes may be made in the construction, arrangement and proportions of the parts without departing from the scope of the invention as defined in the 25 appended claims.

Having thus described my invention, I claim:

1. A device of the character described including a base plate, said base plate ar- 30 ranged for attachment to a shoe and formed

with an interiorly threaded flange, a spike member provided with a plurality of curved circularly arranged flanges engaged with the interior screw threads of the base plate, a concavo-convex disk mounted within the 35 circle of said flanges, the convex face of said disk normally projecting beyond the plane of the edges of said flanges, and a spring within the spike member back of the disk and bearing against the concave face there- 40 of, as and for the purpose described.

2. A device of the character described including a spike member provided with a plurality of curved circularly arranged flanges, a support for said spike member 45 whereby the same may be secured to a shoe, a curved disk mounted within the circle of said flanges, the central portion of said curved disk normally extending beyond the plane of the edges of said flanges, and a 50 spring arranged within the spike member back of said disk and bearing against the same, as and for the purpose described.

In testimony whereof I hereunto affix my signature in the presence of two witnesses. 55

DANIEL A. TRADESCO.
